UNITED STATES PATENT OFFICE.

ADELBERT P. HINE, OF WATERBURY, CONNECTICUT, ASSIGNOR TO COE BRASS MANUFACTURING COMPANY, OF WATERBURY, CONNECTICUT, A CORPORATION OF CONNECTICUT.

MEANS FOR EXTRUDING HOLLOW BODIES.

941,365.

Specification of Letters Patent. Patented Nov. 30, 1909.

Application filed January 9, 1909, Serial No. 471,415. Renewed October 4, 1909. Serial No. 520,971.

To all whom it may concern:

Be it known that I, ADELBERT P. HINE, a citizen of the United States, residing at Waterbury, county of New Haven, State 5 of Connecticut, have invented certain new and useful Improvements in Means for Extruding Hollow Bodies, of which the following is a full, clear, and exact description.

My invention relates to improvements in 10 apparatus for extruding metal to form hollow bodies.

The object of the invention is to provide a simple and efficient means for forming, by an extruding process, hollow bodies of 15 any desired cross-section both internally and externally, which apparatus guarantees by its construction a uniformity of production.

In the drawings: Figure 1 conventionally illustrates, on a small scale, one preferred 20 form of my invention, said figure being mainly in section and showing only such parts as it is necessary to refer to for the purpose of making clear my improvement. Fig. 2 is a side elevation of the parts shown 25 in Fig. 1. Fig. 3 is a section on the line $x-x$ of Fig. 2 looking in the direction of the arrow and showing certain parts in elevation. Fig. 4 is a view on a relatively reduced scale of a modification. Fig. 5 is an 30 end elevation of Fig. 6 on the plane of the line $y-y$ looking in the direction of the arrow and showing certain parts in elevation. Fig. 6 is a section on the line $z-z$ 35 looking in the direction of the arrow and showing parts in elevation.

First referring to Figs. 1 to 3, the construction therein shown comprises a so-called "container" 1, having a cylindrical passage therethrough in which a billet 2 of the metal to be extruded is located. 3 is a die of suitable cross-section and arranged to furnish the desired external contour to the extruded metal. 4 is a mandrel located within the bore of the container 1, the forward end of which stands adjacent to, or in such relation to, the die 3, as to coöperate therewith in the forming of the extruded product. The shape of the mandrel end, in cross-section, corresponds to the desired internal cross sectional outline of the finished product.

In apparatus of this character, great difficulty is found in holding the mandrel properly so that its forward end (which 55 determines the interior conformation of the

hollow extruded body) will be held with sufficient firmness to guarantee an absolutely uniform product.

My invention aims at furnishing the mandrel with a most powerful and effective support. To that end, I mount the rear end of the mandrel upon a powerful supporting bracket 5. This mandrel mounting may be 60 removably connected to the container 1 for the purpose hereinafter described.

6 is a dummy or follower fitting and slideable on the mandrel 4 and fitting the bore of the container 1 and slideable therein.

7 is a plunger operated in any suitable manner, for example, by the usual hydraulic means. This plunger 7 is split or divided at its forward end as best seen in Fig. 2, so as to straddle the bracket 5 whereby the forward extremities of said plunger 7 may be caused to engage the dummy 6 and push it 75 ahead.

From the foregoing the operation will be seen to be as follows: A die 3 of suitable outline is secured in place at the outlet of the container 1, such dies being interchangeable 80 to furnish different designs, as desired. A perforated billet 2 of hot metal to be extruded is then placed in the container. The dummy or follower 6 is then placed in the bore of the container to the rear of the billet 85 2. The mandrel 4 and bracket 5 are then applied, the mandrel being inserted through a central passage in the dummy 6. The bracket 5 is then suitably secured against movement, as by screw studs or bolts 8-8 90 connected with the rear of the container 1. When the parts are thus assembled, the plunger 7 may be advanced to straddle bracket 5 and engage dummy 6, which latter is forced ahead thereby in turn forcing the 95 billet ahead until it engages the die 3. Continued forward movement of the plunger 7 displaces the metal of the billet which flows out through the space around the mandrel 4 and die 3 in such manner as to produce a 100 hollow body of the desired external and internal outline.

In Figs. 4 to 6 inclusive, I have shown a modification in which, instead of splitting the forward end of the plunger so as to cause it to straddle the bracket 5 to which the rear end of the mandrel is connected, I mount said bracket in such a manner as to avoid splitting said plunger. In these figures (4 to 6) 1 represents the container; 2^a 110

the billet; 3^a the die; 4^a the mandrel; 5^a the bracket for the rear end of the mandrel; 6^a the follower or dummy; 7^a the forward part of the plunger, 7^b the intermediate part of the plunger, and 7^c is the piston end of the plunger located within the hydraulic cylinder 9. 10-10 are guides for the plunger in all of the views. As will be seen in Figs. 4 to 6, instead of splitting the forward end 10 of the plunger 7^a, the split occurs at 7^d (Fig. 4) in the intermediate part 7^b of the plunger, said bracket 5^a standing in said split or longitudinal passage so that as the plunger advances, it will not influence the 15 position of the mandrel. In this modification, screw bolts or studs 8^a hold the bracket 5 to one of the guides.

It should be understood that the various parts are made adjustable and dismountable, 20 but the particular means for adjusting or dismounting said parts need not be described since they constitute no essential part of this invention, broadly speaking.

In the preferred construction, in all instances, the main body of the mandrel is 25 made heavier in cross-section than the cross-section of that part of the mandrel which forms the internal wall of the extruded product. By this means great strength and resistance to lateral deflection is afforded. The main body of the mandrel may be 30 round, or of some uniform shape, throughout the greater portion of its length, whereby a snug fit will occur between it and the dummy 6, at all positions of the latter thereon, thus preventing back leakage of the metal past said dummy.

By preference, the body of the mandrel is 35 of circular cross-sectional outline save at its forward forming end where any desired shape may be provided according to the intended internal cross-sectional outline of the extruded metal.

The forward end of the mandrel in each 40 instance may be formed by a removable piece 4^b whereby ends of different designs may be interchangeably employed. The removable ends in all instances are furnished with any suitable attaching means.

It will be observed that the follower serves 45 to support the mandrel against lateral deflection and thus supplements the action of the bracket in this respect.

What I claim is:

1. In a machine for producing hollow tubular bodies, a container having a bore therein, a die carried by said container in line with said bore, a mandrel arranged to coöperate with the die, and means for holding said mandrel in coöoperative relation thereto, a dummy or follower slidable within the container and upon the mandrel and operating as a closure for the space around said mandrel within the die, and means to force said dummy or follower toward the die, independent of the mandrel.

said mandrel in said container, a dummy or follower slidably fitting said mandrel and the wall of said bore, and a plunger arranged to engage the rear of said dummy or follower to force said dummy forwardly on said mandrel and in said bore.

2. In a machine of the character described, a container having a bore therethrough, a die arranged in line with said bore, a mandrel, a bracket for holding the same within said bore and arranged to coöperate with said die, a dummy slidably fitting said mandrel and the wall of said bore, and a power driven plunger movable independently of said mandrel and bracket, and arranged to engage and force said dummy forwardly.

3. In a machine of the character described, a container having a bore therein, a die in line with said bore at the outlet end thereof, a power driven plunger, a mandrel independent thereof and arranged to coöperate with said die, a bracket for holding said mandrel against longitudinal movement and in coöoperative relation with said die, and a dummy or follower having a sliding fit on said mandrel and within said bore, said plunger coöoperating with said follower for the purpose described.

4. In a machine of the character described, a container having a bore of uniform cross-sectional size, a die at the outlet end of said bore having a passage of suitable outline, a mandrel having a forward removable end of a suitable cross-sectional outline adapted to coöperate with said die, means for holding said mandrel in coöoperative relation with said die, a power driven plunger independent of said mandrel, a follower having a sliding fit upon said mandrel and a sliding fit with the wall of said bore, and arranged to be moved forwardly by said plunger.

5. In a machine for extruding hollow bodies, a container having a bore therein, a die carried by said container in line with said bore, a mandrel arranged to coöperate with the die, and means for holding said mandrel in coöoperative relation thereto, a dummy or follower slidable within the container and upon the mandrel and operating as a closure for the space around said mandrel within the die, and means to force said dummy or follower toward the die, independent of the mandrel.

ADELBERT P. HINE.
